Herbert H. Carr,

UNITED STATES PATENT OFFICE

HERBERT H. CARR, OF BOSTON, MASSACHUSETTS.

FOLDING BED.

974,747.

Specification of Letters Patent.

Patented Nov. 1, 1910.

Application filed November 15, 1909. Serial No. 528,240.

To all whom it may concern:

Be it known that I, HERBERT H. CARR, a citizen of the United States, a resident of Boston, in the county of Suffolk and State 5 of Massachusetts, have invented a new and useful Improvement in Folding Beds, of which the following, taken in connection with the accompanying drawings, is a specification.

10 My invention relates to that class of beds that are intended to be folded up when not in use, so that they may not take up any more floor space than is absolutely necessary, and consists in a construction that will 15 cause the base support to be drawn in when the body of the bed is folded and its center of gravity is near the wall, but when the body of the bed is being turned down and the center of gravity passes outward from 20 the wall the base support will be extended outward from the wall and thus resist any tendency of the body of the bed from suddenly pitching forward and falling abruptly to the floor. There are also minor elements 25 that may be best understood by reference to the specifications. These objects I attain by the mechanism shown in the accompanying drawings, in which:—

Figure 1 shows the bed in side elevation, 30 resting upon the floor and in the position the parts occupy when the bed is in use. Fig. 2 shows the bed in side elevation when folded up. Fig. 3 shows the bed in end elevation as it appears when folded up, the body part 35 not being fully shown, the middle part being represented as cut out so as to save space in the drawing. Fig. 4 shows in sectional elevation parts of the base support.

In the drawings the framework of the 40 bed is indicated by A, A¹, A², A³, A⁴ and is constructed substantially as shown in the several drawings. The foot of the bed is supported on the legs L, and the head by the cross rod, D; this cross rod D is rigidly attached to the frame of the bed, its ends acting as bearings and resting in the forked upper ends of the standard B² in which they freely turn. Segment gears E are attached to the ends of the rod, D, and turn with the 45 bed; these segment gears, E, engage with small gears, F, mounted upon the base-bars, B. The gears, F, engage with racks, F¹, see Fig. 4, which slide in ways attached to the base-bars, B, and are connected to the 50 tension bars B¹ by rods F² attached to the

end cross bar, B⁴; by this construction it is evident that when the body frame of the bed is raised up the action of the segment gears and connections will cause the base extension, B¹ B⁴ to be drawn inwardly in the direction of the arrow, Figs. 1 and 4, so that the supporting base will be contracted as shown in Fig. 2. When the bed is being lowered the gears work to throw the extension base outward, that is, in a direction opposed to the arrow, thus preventing the bed from being pulled over in the act of lowering it. Casters C, C¹, C², are attached to the base and serve to admit of easy movement of the bed.

The head board is indicated by H² and is constructed in the usual manner, but is supported by standards H which are made hollow; their lower ends slip over the uprights B³ in the base, see Fig. 4, and are 55 held thereto by the set screws H¹, Figs. 1 and 2; at the upper ends of their standard are clamping pieces H³ H⁴ which securely hold the head board in place. The lower ends of the head board parts H² have inverted U shaped sockets as shown so as to fit the upper part of A⁴ of the body frame, 60 see Fig. 1. A cross rail H⁷ connects the parts H² H²; the section of the rail H⁷ is in the form of an inverted U to correspond 65 with the lower ends of the posts H² H². The upper ends of the part A⁴ are united by a rod A⁵ which engages when the bed is turned 70 down with the U shaped cross rail H⁷.

H⁵ H⁶ represents a frame work which supports curtains for inclosing the bed when it is turned up. The set screws H⁴ hold the said frame in place.

To take the bed frame apart all that is 75 needed to do is to loosen the set screws H¹ and H⁴ and the headboard may be removed and taken apart. The body frame of the bed may be lifted from the standard B² and the whole may be packed together for transportation.

To assist in preventing the abrupt movement of the body of the bed in the act of lowering, springs, S, are connected to the bar D, one end being held to the upright B² and the other end arranged to arrest the 105 downward movement of the bed and yieldingly allow it to go to the floor.

For holding the bedding to the body of the frame when the bed is turned up, I have a tape, T, which is attached to a self rewind- 110

ing drum T^1 at one end as shown in Fig. 2; the other end, after it has been drawn over the bedding is attached to a hook at T^2 .

Claims:

5. 1. A folding bed comprising a body-part having a foot board and foot legs attached; a cross rod attached to the head end of the bed and having end bearings upon which the bed swings as it is turned up; forked standards in the upper end of which the end bearings of the said cross rod swing; a base support having an extension piece, a ratchet device by which the said extension may be operated, segment gears attached to and operated by the said cross bar, spur gear wheels engaging with the said segment gear and the said ratchet device whereby the movement of the bed, in turning up, causes the said base extension to be operated, substantially as and for the purpose set forth.
- 10 2. A folding bed comprising a body frame; standards in the upper end of which the body frame is journaled to swing; a base support having a movable extension member; and means operatively connecting said frame and member whereby the movement of said frame in lowering or raising

the bed operates said base extension member, substantially as and for the purpose set forth.

30

3. In a folding bed, a pivoted body part having at its head end parts (A^4 A^4) and a uniting cross bar A^5 ; a head board having parts (H^2 , H^2) and a uniting U shaped cross bar H^7 constructed to engage with the 35 said uniting cross bar A^5 , substantially as and for the purpose set forth.

35

4. A folding bed comprising a body frame having a foot board and foot legs attached; a base support having standards in which 40 said body frame is journaled to swing; a movable extension member on said base support; and gearing connecting said body frame and extension member, substantially as and for the purpose set forth.

45

In testimony whereof, I have signed my name to this specification in the presence of two subscribing witnesses, on this sixth day of November A. D. 1909.

HERBERT H. CARR.
